UNITED STATES PATENT OFFICE.

JOHN A. WILLIAMSON AND ALICE LOWE WILLIAMSON, OF PARSONS, KANSAS.

BASE-BALL-GAME APPARATUS.

1,164,044.

Specification of Letters Patent.

Patented Dec. 14, 1915.

Application filed April 23, 1915. Serial No. 23,532.

To all whom it may concern:

Be it known that we, JOHN A. WILLIAMSON and ALICE LOWE WILLIAMSON, citizens of the United States, residing at Parsons, in the county of Labette and State of Kansas, have invented new and useful Improvements in Base-Ball-Game Apparatus, of which the following is a specification.

The invention relates to a game apparatus, and more particularly to the class of baseball game apparatus.

The primary object of the invention is the provision of an apparatus of this character wherein the national game of baseball can be successfully played by the use of a suspended ball and images, so that it simulates most all of the features of an actual animate game when being played.

Another object of the invention is the provision of an apparatus of this character wherein the ball when traveling can be struck in a similar manner imitative of an animate batsman when taking part in the playing of an actual game by persons, and additionally, one of the images traverses the diamond similar to the runner in a ball game, while the images positioned at the bases and in the fields are of novel form to assure the catching of the ball when set in action, thereby rendering the game when played attractive and interesting to the participants.

A further object of the invention is the provision of an apparatus of this character wherein the construction thereof in all of its details is novel in form to assure the successful playing of the game, and by the skill of one participant over another will enable the winning of the game when played, and at the same time giving amusement to each and all of the participants.

A still further object of the invention is the provision of a game apparatus of this character which is simple in construction, reliable and efficient in its operation, and inexpensive in manufacture.

With these and other objects in view, the invention consists in the construction, combination and arrangement of parts as will be hereinafter fully described, illustrated in the accompanying drawings, and pointed out in the claims hereunto appended.

In the drawings, Figure 1 is a perspective

view of a game apparatus constructed in accordance with the invention. Fig. 2 is a vertical central sectional elevation therethrough. Fig. 3 is a vertical central transverse sectional view. Fig. 4 is a bottom plan view. Fig. 5 is a fragmentary vertical sectional view through the support for the impelling image to give velocity to the ball. Fig. 6 is a sectional view on the line 6—6 of Fig. 5. Fig. 7 is a top plan view. Fig. 8 is a sectional view through the clamp for the crane or support for the ball. Fig. 9 is an elevation of the movable base for the image indicative of the batsman. Fig. 10 is a sectional view therethrough. Fig. 11 is a sectional view on the line 11—11 of Fig. 7. Fig. 12 is a sectional view on the line 12—12 of Fig. 13. Fig. 13 is a sectional view on the line 13—13 of Fig. 7. Fig. 14 is a sectional view through one of the images. Fig. 15 is a similar view taken through the image indicative of the pitcher. Fig. 16 is a fragmentary sectional view on the line 16—16 of Fig. 7. Fig. 17 is a sectional view on the line 17—17 of Fig. 7.

Similar reference characters indicate corresponding parts throughout the several views in the drawings.

Referring to the drawings in detail, the game apparatus comprises a table A having the pivoted legs B for permitting folding thereof. Located at one corner of the table is a socket ball clamp 10 in which is adjustably mounted the ball terminal 11 of a standard or upright 12, to the upper end of which is linked a crane or arm 13, the link 14 connecting it to the upright 12 serving to permit folding of the crane or arm, the free end of the latter being provided with a guide eye 15, while mounted at the upper end of the upright is a guide eye 16, and through these eyes is trained an adjustable cord or cable 17, the depending free stretch of which has connected thereto a spherical object or ball 18, while the other end of the cable or cord 17 is trained downwardly through an opening in the top of the table A in proximity to the clamp 10, thence is fixed to the handle of an operating lever 21 which is supported at one end for movement upon a pivot 22 fixed in the under side of the top of the table. The lever 21 moves in a guide yoke 23 fixed to the under side of

the top of the table A at one end thereof, and is located approximately centrally of the same, which in its top is formed with an arcuate shaped slot 24 through which is 5 passed the handle 25 rotatably mounted in the lever 21 and forms a windlass 20 for the winding and unwinding of the cord 17 on and from the same to set the height of the spherical object or ball 18 and also to permit the manual shifting of the lever 21 to 10 vary the course of the ball, the yoke 23 medially thereof being formed with a notch 26 to receive a lug 27 formed on the under side of the lever 21 so as to normally lock the 15 latter in neutral position centrally of the table. On slightly lifting the lever 21 by the handle 25 and shifting the latter through the slot 24 in the top of the table A the said cable or cord 17 will be moved for the raising and lowering of the ball 18 relative to the plane of the top of the table, the ball being impelled in a manner presently described.

Located at the center of the table A and 25 mounted in its top is a cup-shaped member 28 which has its upper end flush with the upper surface of the table top, and is formed with a depending central hollow stem 29, the same being rotatably supported in a 30 sleeve 30 fixed in the table top, and on this stem 29 is fixed a pulley 31 over which is trained an endless belt or cable 32 which is also trained over a pulley 33 fixed to a rotatable post or stem 34 journaled in the table 35 top near one end thereof, and carries a hand knob 35 so that on the turning of the stem 34 the cup-shaped member 28 may be adjusted on rotation thereof for a purpose presently described.

40 Pivottally mounted within the cup-shaped member 28 for vertical swinging movement is a disk 36 on which is detachably fastened an image 37, representative of a pitcher, and to this disk is connected one end of a pull 45 cord 38, the same being trained through the stem 29 and guide eyes 39 beneath the table top to a point at one end thereof in convenient reach of an operator, so that the disk 36 can be tilted on the pulling of the cord, 50 the ball 18 being suspended forwardly and in contact with the image 37 so that on the rocking of the image the said ball will be impelled when struck thereby. The image 37 is formed with curved convergent arms 40 55 and 41, respectively, the latter being formed with a hook terminal 42 spaced from the free end of the arm 40 to permit the passing of the ball 18 therebetween, while the hook terminal 42 will catch the ball to retain the 60 same when rebounding on striking the body of the image, and in this manner the ball will be caught thereby.

Surrounding the pivot supporting the disk 36 is a coiled tension spring 43, one end of which is fixed to the cup-shaped member

28, while the opposite end plays against the disk 36, and this spring is designed to return the image to upright position after the tilting thereof and its release by the cord 38 when the same has been freed.

Printed or otherwise indicated on the upper face of the top of the table A is a diamond 44, which is the line of demarcation of the "infield" in contradistinction to the "out-field" of a baseball game area or playing 70 plat. This diamond has arranged at the proper points the usual bases, while detachably mounted on the upper face of the board are a series of images 45 which are located relatively to occupy the positions of first, 75 second and third basemen, short stop, center, right and left fields, catcher, and batsman, respectively. The image indicative of the batsman is mounted for movement in a rotatable and laterally movable base 46 80 which is disposed within an arcuate slot 47 formed in the top of the table A, and is journaled upon a stud 48 fixed in a swinging lever 49 pivoted at one end to the under face of the table top, while mounted in its opposite end is a stem 50, the same being extended upwardly through a guide slot 51 in the table top near one end thereof, and terminates in a hand knob 52 so that the lever 49 can be arcuately moved, while the base 46 90 is adapted for rotation on the stud 48 carried by the said lever. Surrounding the stud is a coiled tension spring 53, one end of which is fixed in the base, and the opposite end in the lever 49, while trained about the 95 base, which is circular or disk-like, is a cord 54, one end of which is connected to the said base, while the other end is extended to the end of the table to be pulled upon by an operator for the tensioning of the spring 53 100 so that on the release of the cord the image 45 mounted in the base will rotate under the action of the said spring, and this image is provided with an arm 55 in which is mounted a bat 56 adapted to strike the ball when 105 impelled for the driving thereof over any portion of the area of the playing field on the table top.

110 The image occupying the position of catcher, located rearwardly of the home plate of the diamond, is formed with arms similar to the arms 40 and 41, while the arm 40 on the image occupying the position of pitcher has connected thereto a resilient member or catch 57 which closes the gap between the terminal 42 of the arm 41 and the arm 40 so that the ball 18 will pass through the gap and be positively caught within the arms of the image, and when it is freely turned to vary the position of the said image 115 for facing the basemen or fielders the ball will be positively held. Arranged rearwardly of the image occupying the position of catcher and fixed to one of the marginal walls 58 of the table is a back stop 59 hav- 120 125 130

ing the laterally extending resilient arms 60 formed with hook terminals 61 so that the ball will be trapped in event the same passes the image occupying the position of catcher.

Formed in the table top and coextensive with three stretches of the diamond 44, and branching from the remaining stretch thereof is a substantially diamond-shaped continuous slot 62, which is the course of the movable image or images 63 serving as the base runners, the images being movable either singly or together in a manner presently described.

Mounted directly beneath the straight stretches of the slot 62 are movable slides 64, each supported in guides 65 fixed to the underside of the table top, while formed in one end of the said table top is a cut-away portion 66 for accommodating a plurality of keys 67, the same being supported upon a pivot 68 common thereto, and suitably mounted beneath the table top so that the said keys 67 can be rocked on the pivot 68. The respective slides 64 have their ends adjacent to each other disposed in overlapping relation directly at the points of the bases. By reason of this particular arrangement, when an image indicative of a runner has been advanced to any one of the bases in the diamond a quick and sudden release of the slide causes an inertia on the part of the said image, and thus freeing the image from the suddenly released slide so that it will gravitate on to the end of the next slide, whereby upon movement of the latter the said image will be correspondingly advanced from one base to the other, and in event that it is desired to move the runner backward the slide is moved gently so that the image will remain upon the slide and move as a unit therewith. Connected to each key 67 is a cord 69, the same being trained over guide pulleys 70 mounted on the table top at suitable points thereof for the proper guiding of the cord, which has its opposite end connected with a hook 71, these hooks being mounted in the slides 64, and to each hook is connected one end of a retractile spring 72, the opposite end of which is connected to one of the guides 65 for each slide 64 so that the same will be moved to normal position after being shifted by actuating the cord 69 connected thereto when the key for controlling such slide is depressed.

The table top is formed with the respective entrance and exit openings 73 and 74 to and from the slots 62 for the positioning of the image or images 63 therein and the removal of the same therefrom. Each image 63 is formed with a base 75 so that it may be placed upon any one of the slides 64 whereby on movement thereof the image 63 will be advanced through the slot 62 from its starting point to the respective bases in-

dicated in the diamond, and at the points of the respective bases the image is shifted from one slide to the other so that the advancement of such image can be carried out successfully throughout the diamond 70 when the keys 67 for controlling the respective slides are operated. The leaning attitude of the image 63 balances the said image. When it is desired to remove the image 63 from the slot 62 it is advanced to the exit 75 opening 73, and in this manner can be readily extracted as will be clearly apparent.

On rotating the cup member 28 the image 37 can be shifted so as to drive the ball in the direction of any of the respective images 80 45 occupying positions at the bases of the diamond 44, thereby enabling "put-outs" counting against the base runners. When the ball 18 has been caught by any of the images it can be readily released by pulling 85 upon the cord or cable 17 for the freeing of the ball from between the arms on the image.

It will be understood that by manipulation of the keys 67 the image indicative of the base runner is moved and also shifted 90 from one slide to another without the necessity of handling the image for this purpose, and also that a plurality of base runners may be advanced to their respective bases at the same time. Upon repeating in quick 95 succession the pressing of the keys down and releasing the same the base runner is carried the entire length of the slide supporting the same and pushed off on to the second or next slide adjacent thereto. The 100 bases are so placed in the diamond that when the base runner is carried as far as the first slide will permit the image indicative of such runner stands at the point of the first base and onto the end next thereto of the 105 adjacent slide so that he is ready to advance from first to second base upon manipulation of the key controlling the said second slide. Each key operates its slide independently so that any combination of keys may be operated at the same time to advance either singly or together four base runners or any number less than four. The base runner in each instance may be advanced around the entire diamond 44 without touching the 110 image indicative of the runner with the hands at any point, and also that a plurality of base runners can run their bases at the same time.

By pressing gently downwardly on the key 120 for operating the initial advancing slide the base runner will be advanced from home plate toward first base, and by quickly lifting the finger from the key the spring and cord suddenly draw the slide back to normal position, leaving the base runner standing in the advanced position. Now, to run backward, the key is suddenly depressed and released gently so that the base runner will be caused to move in a reverse direction in 125 130

the slot 64, and thus it will be seen that the base runner can be moved forwardly or backwardly by proper manipulation of the keys. In this manner of manipulation of the keys it is possible for the base runner to steal off from the base and run back if in danger of being "put-out", and if several base runners are running at the same time and it happens a base is passed by any one of such runners, which often happens when running several base runners at once, a backward movement of the slide slowly brings the image which has passed the base onto the base again, or else a "put-out" would happen. Considerable amusement is had in playing the game by careful manipulation of the keys for controlling the movements of the images indicative of the base runners.

Mounted at one corner of the table is a vertical post C, and any number of these can be mounted at different points of the board so that when the ball is impelled its cord will swing in the path of the post C and become wrapped about the same by the impetus or velocity of travel of the ball, thereby delaying the recovery of the ball and thus indicating an outfield hit, either a long hit or a hit poorly fielded by any one of the images indicative of the outfield players. The upright 12 will also serve as a post for the wrapping of the cord 17 about the same when the ball 18 has been put in motion to prolong the drive to indicate a deep or long outfield hit.

The playing of the game is carried out correspondingly to the rules and regulations of the national game of baseball for the scoring or winning of the game. However, it is to be understood that any number of persons can be participants, yet it requires two operators, one serving to operate the image representing the pitcher and the ball, while the other person operates the images indicative of the batsman and the base runners.

The operation of the apparatus is as follows:—In the playing of the game of baseball it is essential that there be two operators, one disposed at one end of the board and the other at the other end of the board, the same controlling respectively the image indicative of the pitcher, and the other for operating the image indicative of the batsman, and the image indicative of the runner. Assuming that the ball 18 is suspended in position to be struck by the image indicative of the pitcher, the operator pulls upon the cable 38, which tilts the image 37 indicative of the pitcher, the ball being struck by the latter is advanced toward the image indicative of the batter. As the ball reaches the home plate the other operator actuates the cable 54, which causes movement to be imparted to the bat 56 held by the image indicative of the batsman in an

attempt to strike the ball 18, and a failure to accomplish this constitutes a "strike" in the ordinary game of baseball, but should the ball be struck by the bat 56 such will constitute a "hit", provided it is not caught by the images indicative of the "infield" players and "outfield" players, which in this instance will constitute an "out". The operator controlling the movement of the image indicative of the pitcher can, by manipulation of the cable 17, and also the knob 35, cause the ball 18 to travel in the direction of the image indicative of the batsman so that the ball will travel high, low, or in or outside of the plate, and thereby constitute what is known as a "ball", a determined number of which entitle the batsman to take position on first base, as in the ordinary game. Also the operator controlling the batsman can move the image constituting the same by the knob 52 so as to place the ball 18 when hit by the bat 56 at any desirable points in the "infield" or "outfield" in an effort to assure the batsman of a "safe hit". Under any circumstances should the batsman reach first base, either by a "hit" or a "base on balls", it is the object of the operator of the image constituting the runner to advance it from base to base until it reaches the "home plate", and thereby scoring or constituting a "run". The operator manipulating the image constituting the pitcher can dispose the said image in the direction of any of the bases so that the ball 18 can be thrown to the baseman in an effort to prevent the image constituting the runner from advancing from one base to another. In advancing the image constituting the runner, the same is placed in the opening 74 and is moved into the slot 62 so that it can be positioned upon the slide extending from "home plate" to "first base". Now, to advance the image constituting the runner it is necessary to manipulate the key controlling the slide on which the runner is placed so that the slide will be moved in a direction from "home plate" to "first base", and in event that this slide is moved slowly the image constituting the runner and the slide move as a unit. To free the image constituting the runner at "first base" it is necessary that the key be quickly released so that the spring 72 will become active for the quick return of the slide 64 to normal position, and the image constituting the runner, by its inertia, leaves the slide 64 and gravitates on to the end adjacent thereto of the slide 64 extending from first to second base, which in turn is manipulated by one of the keys to advance the runner to the next base, and so on until the runner has reached "home plate". By reason of the fact that the image indicative of the pitcher can be positioned so as to advance the ball in the direction of

the base occupied by the runner, it renders it difficult for the operator controlling the image indicative of the runner to advance the runner from one base to the other, yet 5 this can be done by giving the runner what is known in the ordinary game of ball as a "lead", which is effected by slowly depressing the key controlling the particular slide upon which the runner is positioned. Should 10 the player be advanced too far off the base and an attempt be made to throw the ball in the direction of the base to put the runner out, the pressure can be gradually released from the key, at which time the 15 spring operates to return the slide and runner thereon as a unit to the base previously occupied. Should the runner fail to return to the base previously occupied prior to the arrival of the ball, it is counted as an "out". 20 From the foregoing description, taken in connection with the accompanying drawing, the construction, and manner of operation of the device will be clearly understood, and therefore a more extended explanation 25 has been omitted.

What is claimed is:

1. In a game apparatus of the class described, a board having a continuous circuitous slot of diamond shape, an image 30 movable through the slot, mechanism supported beneath the board for advancing the image through the slot, a plurality of keys for controlling said mechanism, a crane movably supported on the board, a cable guided 35 by the crane, a spherical object connected to the cable, means located centrally of the diamond for giving momentum to the spherical object and simulating a pitcher, and means for striking the spherical object to drive the 40 same at different points of the board and simulating a batsman.

2. In a game apparatus of the class described, a board having a continuous circuitous slot of diamond shape, an image 45 movable through the slot, mechanism supported beneath the board for advancing the image through the slot, a plurality of keys for controlling said mechanism, a crane movably supported on the board, a cable guided 50 by the crane, a spherical object connected to the cable, means located centrally of the diamond for giving momentum to the spherical object and simulating a pitcher, means for striking the spherical object to drive the 55 same at different points of the board and simulating a batsman, and means for actuating the said first-named means.

3. In a game apparatus of the class described, a board having a continuous circuitous slot of diamond shape, an image movable through the slot, mechanism supported beneath the board for advancing the image 60 through the slot, a plurality of keys for controlling said mechanism, a crane movably supported on the board, a cable guided by

the crane, a spherical object connected to the cable, means located centrally of the diamond for giving momentum to the spherical object and simulating a pitcher, means for striking the spherical object to drive the 70 same at different points of the board and simulating a batsman, means for actuating the said first-named means, and means for actuating the second-named means.

4. In a game apparatus of the class described, a board having a continuous circuitous slot of diamond shape, an image movable through the slot, mechanism supported beneath the board for advancing the image through the slot, a plurality of keys 75 for controlling said mechanism, a crane movably supported on the board, a cable guided by the crane, a spherical object connected to the cable, means located centrally of the diamond for giving momentum to the spherical object and simulating a pitcher, means for striking the spherical object to drive the 80 same at different points of the board and simulating a batsman, means for actuating the said first-named means, means for actuating the second-named means, and means for operating the cable to vary the course of the spherical object.

5. In a game apparatus of the class described, a board having a continuous circuitous slot of diamond shape, an image movable through the slot, mechanism supported beneath the board for advancing the image through the slot, a plurality of keys 95 for controlling said mechanism, a crane movably supported on the board, a cable guided by the crane, a spherical object connected to the cable, means located centrally of the diamond for giving momentum to the spherical object and simulating a pitcher, means for striking the spherical object to drive the 100 same at different points of the board and simulating a batsman, means for actuating the said first-named means, means for actuating the second-named means, means for operating the cable to vary the course of the spherical object, and a plurality of images positioned upon the board at predetermined points thereof and having catching arms.

6. In a game apparatus of the class described, a board having a continuous circuitous slot of diamond shape, an image movable through the slot, mechanism supported beneath the board for advancing the image through the slot, a plurality of keys for controlling said mechanism, a crane movably supported on the board, a cable guided by the crane, a spherical object connected to the cable, means located centrally of the diamond for giving momentum to the spherical object and simulating a pitcher, means for striking the spherical object to drive the 115 same at different points of the board and simulating a batsman, means for actuating the said first-named means, means for operating the cable to vary the course of the spherical object, and a plurality of images positioned upon the board at predetermined points thereof and having catching arms.

actuating the second-named means, means for operating the cable to vary the course of the spherical object, a plurality of images positioned upon the board at predetermined points thereof and having catching arms, and a backstop on the board for the spherical object.

Copies of this patent may be obtained for five cents each, by addressing the "Commissioner of Patents, Washington, D. C."

In testimony whereof we affix our signatures in presence of two witnesses.
